UNITED STATES PATENT OFFICE

ALFRED J. FLAUDER, OF TRUMBULL, CONNECTICUT, ASSIGNOR TO THE WEIDLICH BROS. MFG. CO., OF BRIDGEPORT, CONNECTICUT, A CORPORATION OF CONNECTICUT

DESIGN FOR A PEDESTAL OR ANALOGOUS ARTICLE

Application filed December 31, 1931. Serial No. 42,323. Term of patent 7 years.

To all whom it may concern:

Be it known that I, ALFRED J. FLAUDER, a citizen of the United States, and a resident of Trumbull, in the county of Fairfield and State of Connecticut, have invented a new, original, and ornamental Design for a Pedestal or Analogous Article, of which the following is a specification, reference being had to the accompanying drawings, forming a part thereof, and in which:

Fig. 1 is a plan view of a pedestal or analogous article, showing my new design; and

Fig. 2 is a front elevation of the same adapted for use as a base upon which trophies may be mounted.

The opposite side of the pedestal shown in Fig. 2 bears ornamentation substantially the same as that shown on the front.

I claim:

The ornamental design for a pedestal or analogous article substantially as shown and described.

Signed at Bridgeport in the county of Fairfield and State of Connecticut, this 30th day of December, 1931.

ALFRED J. FLAUDER.
